REVOLVING DOOR

Edmund Peremi, Manhasset, and Charles Kish, Elmhurst, N. Y., assignors to General Bronze Corporation, Long Island City, N. Y., a corporation of New York

Application September 17, 1932, Serial No. 633,584

9 Claims. (Cl. 20—18)

This invention relates to revolving doors. In such doors as commonly employed at the present time the leaves of the door are made to fold so that in warm weather or upon other occasions when it is desired to provide an open passage through the door the leaves may be folded up and the central column of the door with the leaves thereon pushed to one side of the opening. In order to accomplish this result the door column is suspended from a trolley running on a track mounted above the ceiling of the door enclosure. A slot is provided in such ceiling for the door column. One object of the present invention is to provide a closure for such slot which will be automatically closed when the door is moved to central position and which will open when the door is pushed to one side. In revolving doors as now constructed it is customary to leave the slot uncovered at all times and this permits drafts to blow through the slot and seriously interferes with the tightness of the structure.

Another object of the invention is to provide improved latching means for locking the door trolley at the limits of its travel, such latching means being so constructed as to automatically engage and latch the trolley in position when it reaches the ends of its travel and to be operated by the swinging movement of the door column to release the trolley when the column is pushed one way or the other. No special latch operating mechanism extending up through the column is therefore required.

Other objects and advantages of the invention will appear from the following detailed description of certain preferred embodiments of the invention chosen to illustrate the principles thereof.

In the accompanying drawings,

Figure 1 is a diagrammatic view partly in side elevation and partly in vertical section showing a door housing with a trolley mounted above the same and the door depending from said trolley, the door being shown folded and swung to one side so as to release the latch preparatory to moving the trolley and door to the side of the door opening;

Figure 2 is a diagrammatic view partly in plan and partly in horizontal section showing the ceiling above the door opening and the slot closing means mounted thereon, the door being indicated by dotted lines on one side of the drawings;

Figure 3 is a plan view of the slot closing means on an enlarged scale, the door column being shown in section and the slot closing means being shown closed;

Figure 4 is a similar view showing the slot

closing means starting to open as the door column is pushed to the right;

Figure 5 is a vertical section on the line 5—5 of Figure 3;

Figure 6 is a plan view of a door supporting trolley and governor mechanism mounted thereon, the cover of the governor mechanism being removed;

Figure 7 is a detail, vertical section on line 7—7 of Figure 6;

Figure 8 is a longitudinal, vertical section taken approximately on the line 8—8 of Figure 6;

Figure 9 is a view partly in side elevation and partly in longitudinal vertical section showing a modified construction of the door trolley and latch operating means; and

Figure 10 is a plan view of the structure shown in Figure 9.

Referring to the drawings in detail, 20 is a door enclosure which comprises the curved wall sections 21, the ceiling 22 and the floor 23. In the ceiling 22 is a slot 24 for the door column. Mounted above the ceiling are channelled rails 25 constituting a track for the door trolley 26 which is provided with wheels 27 running on the track. Fixed to the track are stops 30 and 31 provided with striker blocks 32 and 33. Mounted on the trolley are latches 34, 35 adapted to engage with the respective striker blocks. The latches are pivoted on pins 36 and each is provided with an operating arm 37. The door comprises a central column 40 on which are pivotally mounted in any suitable manner a plurality of leaves 41, illustrated as four in number. Means are provided whereby the leaves may be locked in radial position when the revolving feature of the door is being utilized, such means being well understood and therefore not being illustrated in detail herein. The leaves may also be folded together in any well understood manner so as to permit the door to be moved to one side of the door opening. For instance, the leaves may be folded in pairs extending diametrically from the door column as shown in dotted lines in Figure 2. The column

40 is suspended from the trolley by means of a block 45 fixed on the column which bears on a suitable anti-friction bearing 46 which is mounted in a carrier member 47. The carrier member 47 is supported on the trolley frame in such manner as to permit of a limited universal movement of the door column so as to permit the latter to hang vertically and insure the free movement of the door in its housing and also to permit actuation of the latches in the novel manner herein-after explained. To secure the universal move-

ment described any well known means may be employed. In the construction illustrated, the bearing member 47 is provided with cylindrical bearing surfaces 48 which rest in correspondingly shaped grooves in the gimbal ring or cradle 49. The gimbal ring or cradle is provided with trunnions 50 which rest in recesses 51 in the side members of the trolley frame. The block 45 and door column are preferably further supported in true position with respect to the carrier 47 by means of an anti-friction bearing 55. In the construction illustrated, the carrier block 47 also carries a governor housing 60 to be described more in detail below and the corner 61 of this governor housing is adapted to engage the arm 37 of the latch 35 to release such latch when the door column is pushed towards the right as shown in Figure 1 so as to tilt the carrier block 47 and gimbal ring on the trunnions 50. When the door column is swung in the opposite direction a horn 62 carried by the carrier block 47 is adapted to engage the arm 37 of the other latch 34.

Assuming the door to be in central position in the door housing and the door column to be vertical, the latch 35 will be in engagement with the striker block 33 and the trolley locked in central position over the door housing. At its lower end the column will be held in central position by the usual bottom pivot 56 fitting in a socket in the floor. If it be desired now to move the door to one side of the door housing, the leaves will first be folded up as shown in Figures 1 and 2 and the bottom pivot retracted from the floor socket in the usual manner. The door is then simply pushed towards the right. This will first cause the column to swing to one side as shown in Figure 1 and will bring the corner 61 of the governor housing into engagement with the latch arm and release the latch 35, whereupon the door and trolley will move to the right. When the door reaches the limit of travel it will be stopped by engagement of the end of the trolley with the striker block 32 and at the same time the latch 34 will ride over the surface of the striker block 33 and engage behind the same, thereby locking the trolley in its side position. To return the door to central position the door is merely pulled out towards the center whereby at first it will swing to the left and release the latch and then the trolley will move towards the center until the latch 35 engages with the striker block 33. The latching and unlatching of the trolley is thus practically automatic and requires no attention on the part of the operator other than a push or a pull on the door. No special operating mechanism passing up through the door column is required for actuating the latches. The latches also automatically set themselves so as to engage with the respective striker blocks when the door is moved to one side or the other.

For closing the slot 24 in the ceiling when the door is in its central position, a slot cover 70 is provided which slides on top of the ceiling and is secured thereto by a plurality of links 71 which are pivoted to the slot cover at 72 and to the ceiling at 73. These provide for parallel motion of the slot cover diagonally across the slot 24. The edge of the slot cover is preferably beveled as indicated at 75 so that it will slide freely over the edge of the slot without catching. The end of the slot cover 70 nearest to the center of the door has attached thereto a plate 80 which has a recess 81 adapted to receive the door column, the portion of the plate beyond the door column being extended across the slot to provide a finger

82 which will be engaged by the door column when moved towards the left (Figures 1, 2, 3 and 4). This movement will cause the slot cover to be moved laterally and towards the left so as to completely close the slot except for the hole through which the door column passes, as shown in Figure 3. To hold the slot cover firmly over the slot in this position lugs 83 are provided which engage with the edge of the slot cover. When the door is moved towards the right, column 40 engages with the face 85 of the recess in the plate 80, as shown in Figure 4, and pushes the slot cover towards the right. Owing to its pivotal mounting upon the links 71 this causes the slot cover to be drawn laterally so as to uncover the slot 24 and permit the door to be pushed to one side. It is thus seen that the slot is covered and uncovered automatically as the door is pushed from its side to its central position and vice versa.

In order that the speed of rotation of the door may be regulated to a desired maximum, and spinning prevented, governing means are preferably provided, and we have shown in Figures 6, 7 and 8 a preferred form of friction regulating means for this purpose. As here illustrated, the carrier member 47 of the trolley is provided with a governor housing 60. Fixed on the upper end of the door column 40 is a gear 90 which extends into the governor housing and meshes with a pinion 91 mounted on a shaft 92 supported in a bearing 93 in the lower part of the governor housing and in a bearing 94 in the cover plate of the housing. Also fixed to the shaft 92 is a rotary table 100 which carries the governor mechanism. A pair of brake shoes 101 are provided which are pivoted on pins 102 which are mounted in the table and in bracket plates 103 fixed to the table by means of screws 104 and 105. The brake shoes are provided with strengthening ribs 110 and with surfaces of suitable friction material 111 which engage with the inner surface 112 of the housing, such surface constituting a stationary brake drum. Centrifugal means are provided for causing the brake shoes to engage the brake drum, such means comprising the weights 115 mounted on the ends of levers 116 which are pivoted on pins 117 in the bracket plates 103. The levers 116 are preferably channel shaped, as shown in Figures 7 and 8, and are provided with lugs 120 which engage with lugs 121 on the brake shoes, as shown in Figure 6, whereby the centrifugal force of the weights 115 is applied to the brake shoes in multiplied ratio, depending upon the relative lengths of the lever arms. For holding the brake shoes out of engagement with the brake drum until the desired maximum speed has been reached and in order to regulate such speed, springs 125 are provided which bear against surfaces 126 on the bracket plates 103 and which are connected to the brake shoes by means of rods 127 engaging pins 128 on the brake shoe ribs 110. The tension of the springs 125 may be adjusted by means of nuts 130 screwing on the ends of rods 127. The springs draw the brake shoes away from the brake drum until a sufficient speed of rotation is reached to cause the centrifugal force of the weights 115 to overcome the spring tension, whereupon the braking force will be applied and the speed of the door checked. Until this speed is reached no braking effect is produced and the door revolves freely. By adjusting the tension of the springs by means of the nuts 130 the speed at which the braking force will be applied may be varied.

The governor construction disclosed in this application is not claimed herein as the same forms the subject matter of a divisional application about to be filed.

5 In Figures 9 and 10 we have illustrated a modified construction of door trolley in which no brake mechanism is provided but having latches and means for operating same in the manner already described. As shown in these figures, 10 the main frame of the trolley is similar to that already illustrated, and is provided with latches 34 and 35. The door column 40 carries a block 45 which is mounted on a thrust bearing 46 carried in a modified form of carrier 41a. This 15 carrier 41a is supported in a gimbal ring 49 by means of cylindrical lugs 48 and the gimbal ring is supported by means of trunnions 50 mounted in recesses 51 in the trolley frame as described above. The carrier 41a is provided with a pair 20 of latch actuating horns 140, one or the other of which is adapted to engage with the arm 37 on one or the other of the latch members, depending upon which way the door column is swung. A cover plate 152 is preferably provided on the 25 upper end of the door column so as to protect the bearing 46 from dirt which might fall into the recess in the carrier 41a.

While we have illustrated and described in detail certain preferred forms of our invention, 30 it is to be understood that changes may be made therein and the invention embodied in other structures. We do not, therefore, desire to limit ourselves to the specific constructions illustrated, but intend to cover our invention broadly in what- 35 ever form its principle may be utilized.

We claim:

1. In a revolving door, a door enclosure including a ceiling having a slot therein, a door having a column passing through said slot and 40 having door leaves pivotally mounted upon said column, a trolley mounted above said ceiling from which said column is suspended, and a cover plate for said slot mounted to slide in the plane of the ceiling into and out of position to cover 45 said slot.

2. In a revolving door, a door enclosure including a ceiling having a slot therein, a door having a column passing through said slot and having door leaves pivotally mounted upon said 50 column, a trolley mounted above said ceiling from which said column is suspended, and a cover plate for said slot movable diagonally across said slot in the plane of the ceiling and actuated by the movement of the door column along said slot 55 so as to open said slot when the door column is moved to one side of the door enclosure and to close said slot when the door column is moved to the center of the door enclosure.

3. In a revolving door, a door enclosure including a ceiling having a slot therein, a door having a column passing through said slot and having door leaves pivotally mounted upon said column, a trolley mounted above said ceiling from which 60 said column is suspended, and a cover plate for said slot movable diagonally across said slot in the plane of the ceiling and actuated by the movement of the door column along said slot so as to open said slot when the door column is moved to one side of the door enclosure and to 65 close said slot when the door column is moved to the center of the door enclosure, the means for causing said cover plate to be moved comprising parallel links pivoted to said cover plate and to said ceiling and an actuating plate attached 70 to said cover plate and having a finger extending 75

across said slot to be engaged by the door column when moved toward the center of the door enclosure.

4. In a revolving door, a door enclosure including a ceiling having a slot therein, a door having a column passing through said slot and having door leaves pivotally mounted upon said column, a trolley mounted above said ceiling from which 5 said column is suspended, and a cover plate for said slot movable diagonally across said slot in the plane of the ceiling and actuated by the movement of the door column along said slot so as to open said slot when the door column is moved to one side of the door enclosure and to close said slot when the door column is moved 10 to the center of the door enclosure, said cover plate having a beveled edge on the side passing over the slot.

5. In a revolving door, a door enclosure including a ceiling having a slot therein, a door 20 having a column passing through said slot and having door leaves pivotally mounted upon said column, a trolley mounted above said ceiling from which said column is suspended, and a cover plate for said slot mounted to slide in the plane 25 of the ceiling into and out of position to cover said slot, said cover plate having a U-shaped recess therein facing one edge of the cover plate and adapted to receive said column when the cover plate is closed.

6. In a revolving door, a door enclosure, a track mounted above the same, a trolley movable on said track, a door column suspended from said trolley by means permitting swinging movement of the door column, door leaves pivoted upon said 30 column, and latch means for locking said trolley in position upon said track, said means being operable by the swinging movement of the door column to unlatch the trolley.

7. In a revolving door, a door enclosure, a track 40 above the same, a trolley travelling on said track, stops fixed to said track adapted to stop said trolley in positions near the side of the door enclosure and near the center thereof, latches pivoted to said trolley and adapted to latch said 45 trolley against one or the other of said stops, a door column, door leaves pivotally mounted on said column, a carrier member for supporting said door column from said trolley, said member having limited universal movement with respect 50 to said trolley, and means on said carrier member adapted to be brought into engagement with one or the other of said latches so as to release the same by a swinging movement of the door column.

8. In a revolving door, a door enclosure, a track above the same, a trolley travelling on said track, stops fixed to said track adapted to stop said trolley in positions near the side of the door enclosure and near the center thereof, latches pivoted to said trolley and adapted to latch said trolley against one or the other of said stops, a door column, door leaves pivotally mounted on said column, a carrier member for supporting said door column from said trolley, said carrier 60 member having a recess therein in which is mounted an anti-friction bearing, said door column having a bearing block fixed thereto resting on said bearing, said column also having a gear fixed thereto, a governor housing carried 65 by said carrier member having governor mechanism therein, a driving pinion for said governor mechanism meshing with said gear, a gimbal ring pivotally mounted on said trolley, means for pivotally supporting said carrier member on said 70 75

gimbal ring, a portion of said governor housing being adapted to engage and release one of said latches when the door column is swung in one direction and means on the carrier member for engaging the other latch to release the same when the door column is swung in the opposite direction.

9. In a revolving door trolley, a frame, wheels mounted on the frame, latches movably mounted

on the frame, a door column carrier member mounted on the frame in such a way as to have tilting movement with respect thereto, and means carried by said carrier member and operated by tilting movement of the carrier member to actuate said latches.

EDMUND PEREMI.
CHARLES KISH.
